UNITED STATES PATENT OFFICE.

JAMES C. HAMILTON, OF ARLINGTON HEIGHTS, MASSACHUSETTS.

PENCIL.

1,327,038.

Specification of Letters Patent.

Patented Jan. 6, 1920.

Application filed February 26, 1919. Serial No. 279,324.

To all whom it may concern:

Be it known that I, JAMES C. HAMILTON, a citizen of the United States, residing at Arlington Heights, in the county of Middlesex and State of Massachusetts, have invented a new and useful Pencil, of which the following is a specification.

This invention relates to pencils of the type in which the lead and the holder therefor are relatively movable whereby to expose the point for writing, and particularly to a pencil of this type provided with a sharpener or pointer for the lead.

One factor which has seriously complicated the successful development of a sharpener-equipped pencil of this class is the characteristic brittleness of the lead itself, and the difficulty of so supporting the lead within the holder so as to prevent breakage of the lead in the operation of sharpening the point while yet readily permitting the desired movement of the point into and out of writing position.

To the end therefore of providing a pencil of this type which will afford adequate protection against breakage of the lead in the sharpening operation without interfering with the ready adjustment of the lead, and which will be at once of neat and attractive appearance and of simple and inexpensive construction, I have devised my present invention. According to my invention, the lead or other marking substance is freely movable through a guide fixed in the holder near the writing end thereof, and the guide is so formed as to expose only a relatively small portion of the lead at a time to the action of the pointer, backing and supporting the major portion of the lead in such manner as to prevent the lead breaking under the action of the sharpener. The lead may be rotated in the guide relative to the sharpener whereby to produce a symmetrical point, and the sharpener itself is so arranged and formed as not to interfere with the ordinary use of the pencil in writing while yet constantly available for action upon the lead and adapted to be instantly and readily brought into effective working relation to the lead by simple pressure of the thumb or finger. The arrangement is such, moreover, that the sharpener may be adjusted relative to the lead so as to always present a new abrasive surface thereto, thus

insuring even distribution of the wear upon the sharpener and proper pointing of the lead. These and various other features of advantage which will appear more particularly hereinafter are secured in the device of the present invention, the construction and manner of use of which, together with a preferred embodiment illustrative of the principles involved, is described in the following specification, illustrated in the accompanying drawings, and particularly pointed out in the appended claims. Throughout the specification and drawings like reference characters are correspondingly applied, and in the drawings:

Figure 1 is an elevation of a pencil in accordance with my invention, and showing the point exposed for use.

Fig. 2 is a longitudinal section thereof, on the line 2—2 of Fig. 1, particularly illustrating the relation of the parts in the operation of pointing the lead.

Fig. 3 is a transverse section on the line 3—3 of Fig. 2, and

Fig. 4 is a detail view of the upper end of the barrel or casing.

Fig. 4^a is a section on the line 4^a—4^a, Fig. 2.

Fig. 5 is a detail view of the point guiding and supporting member, removed, and

Fig. 6 is a detail section similar to Fig. 3 and showing a modified form of sharpener.

I have indicated at 1 a barrel or casing, and at 2 a lead holding tube rotatably mounted within said barrel and longitudinally split to receive and frictionally clamp leads 3 of varying diameter inserted therein. The lead holder 2 may be compressed to grip the lead by means of a split collar 7 slidable thereon over an external protuberance 8 arranged on the lead holder. When the collar is engaged with said protuberance, the lead is frictionally clamped within the holder 2, and the collar itself is locked against relative movement. By disengaging the collar, as represented in Fig. 2, the lead may be adjusted within the holder from time to time as it wears down.

One end of the lead holder is made fast, as indicated at 2', to a cap 4 rotatably mounted upon the upper end of the barrel, which as here shown is provided with a longitudinally extending bayonet slot 5 in which works a stud 6 on the cap. This con-

struction permits the pencil point to be moved into and out of writing position and to be sharpened.

Beyond the lower end of the holder 2, the 5 lead freely guides within a bushing 9 fixed within the barrel near the lower end thereof, as indicated at 9'. Between the guide 9 and the barrel a sharpener or pointer 10 is mounted to act upon the lead exposed there- 10 to through a cut-away portion 9^a, Fig. 5, of said guide. The solid bottom wall of the guide, considering the parts in the relation shown in Fig. 2, affords backing and support to the major portion of the lead dis- 15 posed within the guide, and since only a relatively small portion of the lead is exposed at a time to the sharpener through the cut-out 9^a, the liability of the lead breaking during sharpening is reduced to the 20 minimum.

As shown in Figs. 2 and 3, the sharpener 10 is adapted to be brought into effective relation to the lead by the depression of a spring tongue formed from the material 25 of the barrel at the lower end thereof by slotting the barrel, as best shown in Fig. 1. Normally, the presser 11 lies in the plane of the barrel and the sharpener is out of contact with the lead, but when it is desired to 30 bring the sharpener into action, the tongue 11 is depressed to carry the abrasive against the lead, which is pointed by being moved therewith by means of the cap 4.

In Figs. 2 and 3, the sharpener is shown 35 as an abrasive surface, such as emery or sand-paper, rolled into cylindrical form and loosely confined about the guide so as to be capable of rotating slightly as the lead is being sharpened whereby to evenly dis- 40 tribute the wear throughout the entire abrading surface and to always present a sharp abrading surface to the lead. In Fig. 6, the sharpener is shown as a simple strip of material having an abrading surface 12 45 and secured directly to the inner face of the tongue 11.

Normally, the point is retracted within the barrel so as to be protected thereby. In this position the stud 6 of the cap locks in 50 the notch 5' near the rear end of the bayonet slot 5. When it is desired to write, the lead is advanced to the position shown in Fig. 1 by sliding the cap, and with it the lead holder 2, forwardly along the barrel 1 until 55 the stud 6 locks in the notch 5^a at the forward end of the bayonet slot. When it is necessary to sharpen the point, the stud is withdrawn wholly from the bayonet slot through the open end 5^b thereof, as shown 60 in Fig. 2, so that when the cap is rotated, and with it the lead holder 2, the lead will move past the sharpener. With the parts in this position, the spring tongue 11 is depressed to carry the sharpener into contact 65 with the lead exposed thereto through the

cutaway portion 9^a of the guide. The lead holder may be refilled from the position of Fig. 2 by bodily withdrawing it from the barrel, disengaging the collar 7 from the protuberance 8 to unclamp the old lead, 70 inserting a new lead, returning the collar to its tube-clamping position, and replacing the holder within the barrel. The abrasive 10 may also be renewed when necessary, as by removing the lead holder from the 75 barrel, inserting a suitably hooked instrument into the barrel to engage and withdraw the bushing 9, removing the old abrasive, substituting a new, and replacing the parts, or the tongue 11 may be drawn out- 80 wardly to uncover the abrasive through the slot formed in the barrel in producing the tongue, the old abrasive removed through said slot, and a new substituted.

Various modifications in the construction 85 and arrangement of the parts comprising my device may obviously be made within the limits of the appended claims.

I claim:

1. A pencil comprising a barrel having a 90 relatively stationary lead guide adapted to support a lead against breakage in sharpening and cut away at one side to expose a portion of the lead therein to a sharpener, a normally ineffective sharpener mounted for 95 action upon the lead exposed through said cut-away portion of the guide at a point above the lower end of the guide, a digitally-operated member mounted on the barrel and adapted upon operation to carry the sharpener into contact with the lead, and means 100 for moving the lead and sharpener relative to each other.

2. A pencil comprising a barrel having a 105 relatively stationary guide adapted to support a lead against breakage in sharpening and cut-away at one side to expose a portion of the lead therein to a sharpener, a normally ineffective sharpener mounted between the guide and the barrel for operation 110 upon the lead exposed thereto through said cut-away portion of the guide at a point above the lower end of the guide, a spring tongue formed on the barrel and adapted upon operation to carry the sharpener into contact with the lead, and a cap 115 adjustable upon the barrel and adapted to move the lead past said sharpener.

3. A pencil comprising a barrel, a lead 120 therein adapted to be sharpened by rotation, and an abrasive element arranged within said barrel for sharpening action upon the lead and automatically rotated by the lead during the rotation thereof in sharpening to present different abrasive surfaces to the 125 lead.

4. A pencil comprising a barrel having a lead guide, a spring tongue fixed against longitudinal movement upon the barrel and normally disposed out of the plane of the 130

lead and adapted to be moved toward the lead, and a normally ineffective sharpener mounted between said tongue and the lead and movable by said tongue into sharpening contact with the lead.

5. A pencil comprising a barrel, a lead guide fixed therein and having a cut-out at one side of its longitudinal axis through which the underlying portion of a lead to be pointed is exposed, a sharpener overlying said cut-out and adapted to be pressed into sharpening contact with the lead exposed through said cut-out, the guide at the opposite side of its longitudinal axis presenting a backing and supporting surface to the lead opposite said sharpener whereby to meet the breaking strain imposed on the lead by the pressure of the sharpener thereagainst, and means for moving the lead and sharpener relatively.

6. A pencil comprising a barrel, a lead guide mounted therein and having a cut-out at one side of its longitudinal axis through which the underlying portion of a lead to be pointed is exposed, a sharpener mounted opposite said cut-out and adapted to be pressed into sharpening contact with the lead exposed through said cut-out, the side of the guide opposite said cut-out backing and supporting the lead against the breaking strain imposed by the pressure of the sharpener against the lead, and means for moving the lead relative to the sharpener.

35. 7. A pencil comprising a barrel, a lead guide fixed therein and having a wall adapted to back and support a lead against breakage and having a cut-out opposite said wall, through which the underlying portion of the lead to be pointed is exposed, and a sharpener mounted opposite said wall and adapted to be moved into sharpening contact with the lead exposed through said cut-out.

45. 8. A pencil comprising a barrel, a supporting and backing sleeve for a lead mounted therein, said sleeve having a longitudinally extending cut-out between its ends through which the underlying portion of the lead is exposed for sharpening, and a

sharpener active upon said lead exposed through said cut-out to point the same.

9. A pencil comprising a barrel, a supporting and backing sleeve for the lead mounted therein, said sleeve having a cut-out between its ends through which the underlying portion of the lead is exposed for sharpening, an abrasive element exposed through said cut-out for action upon the lead and loosely mounted to rotate as the lead is sharpened whereby to present different abrasive surfaces to the lead, means for holding the abrasive element in contact with the lead, and means for moving the lead past said abrasive element.

10. A pencil comprising a barrel having a lead guide, said barrel slotted adjacent the lead guide to provide a spring tongue fixed against longitudinal movement relative to the barrel and normally disposed out of the plane of the lead and adapted to be moved toward the lead, and a normally ineffective sharpener mounted adjacent said tongue and adapted to be carried by said tongue into sharpening contact with the lead.

11. A pencil comprising a barrel, a lead guide fixed therein, a lead movable in said guide, and a normally ineffective sharpener disposed for action upon the lead, said barrel slotted adjacent the guide to provide a spring tongue fixed against longitudinal movement relative to the barrel and normally disposed out of the line of movement of the lead and movable toward the lead to carry the sharpener into sharpening contact therewith.

12. A pencil comprising a barrel, a lead guide within said barrel, a lead rotatably and longitudinally movable in said guide, and a sharpener consisting of a lapped sheet of abrasive material rolled about the guide as a core and adapted to be moved into sharpening contact with the lead.

Signed at Boston, in the county of Suffolk, and State of Massachusetts, this 24 day of February, 1919.

JAMES C. HAMILTON.
